UNITED STATES PATENT OFFICE.

OVID COHEN, OF NEW HAVEN, CONNECTICUT.

DESIGN FOR A BADGE.

SPECIFICATION forming part of Design No. 35,825, dated March 25, 1902.

Application filed February 27, 1902. Serial No. 96,023. Term of patent 8½ years.

To all whom it may concern:

Be it known that I, OVID COHEN, a citizen of the United States, residing at New Haven, in the county of New Haven, State of Connecticut, have invented and produced a new and original Design for Badges, of which the following is a specification, reference being had to the accompanying drawing, forming a part thereof, and in which the figure is a plan view of my design.

As shown by the drawing, the design embodies as its essential feature a flag-shaped piece A, which is surmounted by a figure of an eagle B with outspread wings, perched on the figure of a globe C, shown resting between a branch of laurel D and a branch of palm E, and surmounted by ribbons F, said branches of laurel and palm having pending from the stems thereof a pick G, shovel H, and spade I, the whole constituting an ornamental and fanciful pendant for said flag-shaped piece A.

Other minor features of the design are the ornamentation of the globe and the configuration of the pendant, which, as will be seen, shows the handles of the shovel and spade 25 crossed on the handle of the pick, with the outer end of the handle of said shovel and spade bearing on the outer ends of the pick-handle.

Having described my invention, what I 30 claim, and desire to secure by Letters Patent, is—

The design for a badge, substantially as herein shown and described.

In witness whereof I have hereunto set my 35 hand, at New Haven, in the county of New Haven, State of Connecticut, this 24th day of February, 1902.

OVID COHEN.
